DESIGN FOR A GAME BOARD

Henry C. Stoll, Bronx, N. Y.

Application October 24, 1939, Serial No. 87,834

Term of patent 14 years

To all whom it may concern:

Be it known that I, Henry C. Stoll, a citizen of the United States, residing at Bronx, county of Bronx, and State of New York, have invented a new, original, and ornamental Design for a Game Board, of which the following is a specification, reference being had to the accompanying drawing, forming part thereof.

Fig. 1 is a plan view of a game board embodying my new design.

Fig. 2 is a cross-sectional view taken substantially on the line 2—2 of Fig. 1.

The dominant features of the design consist in a circular game board having an inclined border extending inwardly and upwardly from the extreme sharp edge of the board and merging into a bead-like portion surrounding a depressed circular field containing rows of circular seats forming a square figure disposed in the center of said field, all substantially as shown.

I claim:

The ornamental design for a game board, substantially as shown and described.

HENRY C. STOLL.
